BATHTUB

Walter D. Teague, Annandale, N. J., and Robert J. Harper, Scarsdale, and Alban G. Jackson, New York, N. Y., assignors to American Radiator & Standard Sanitary Corporation, New York, N. Y., a corporation of Delaware

Application December 9, 1955, Serial No. 39,269

Term of patent 14 years

(Cl. D4—4)

Fig. 1 is a perspective view of a bathtub shown in reduced scale embodying our new design,

Fig. 2 is a top plan view of the bathtub,

Fig. 3 is a view in front elevation of the bathtub, and

Fig. 4 is a view of the bathtub in section on the line 4—4 of Fig. 2.

We claim:

The ornamental design for a bathtub, substantially as shown.
